By C. M. Wright, Jr.
Attorney

UNITED STATES PATENT OFFICE

PERCY C. AVERY, OF WEST ALLIS, WISCONSIN, ASSIGNOR TO ROBERTA S. FOSSE, OF WASHINGTON, DISTRICT OF COLUMBIA

RADIATOR FOOT REST

Application filed May 2, 1928. Serial No. 274,645.

My invention relates to improvements in radiator foot rests.

The object of my invention is to provide a foot rest for radiators which can be readily attached to the ordinary radiator between any of the vertical coils thereof, and so constructed that the same has a very small contacting point with the coils, so that there will be practically no heat conducted from the coils of the radiator to that portion of the foot rest upon which the feet rest.

Another object of my invention is to provide a foot rest of this character which is neat in appearance, simple in construction and can be readily applied and removed, and having certain details of structure and combination of parts hereinafter more fully set forth.

In the accompanying drawings:

Figure 1 is a perspective view of a radiator showing my improved foot rest applied thereto.

Figure 2 is a horizontal sectional view showing more fully the attaching means.

Figure 3 is a rear elevation showing the attaching bolts in section.

Referring now to the drawings, 1 represents the radiator which, for the purpose of illustration, is provided with vertically disposed coils spaced apart, and while I have shown this specific form of coil it will be understood that my invention can be applied to any form of radiator having the heating elements spaced apart in vertical relation.

My improved foot rest consists of two pieces of rolled steel rod 2 and 3, each piece having a loop 4 formed therein, terminating in the straight portions 5 and 6 arranged parallel and bent around as indicated at 7, forming the two straight parallel horizontal portions 7' and 8 which have their ends abutting against the ends of the other member, and the ends are electrically welded to each other at the points 9 and 10, and plates or washers 11 and 12 are electrically welded thereto as clearly shown in Figures 2 and 3 of the drawings, or may be held thereon by a rivet 13. The attaching bolts 14 are of a T shaped form, as shown in Figure 2 of the drawings, having their outer ends thread-

ed as indicated at 15, and the head 16 of the bolts engages the rear edges of the heating coils. The bolts proper extend outwardly between the portions 5 and 6 of the looped ends 4. Arranged on the bolts on the outside of the loop 4 are washers 17 which are clamped against the loop 4, by means of the nuts 18, whereby the loop 4 is clamped against the outer edge of the heating coils.

By this structure it will be seen that the narrow edges of the heating coils engage the two rods of the loop 4 and thus very little heat would be conducted from the coils to the loop and practically no heat would be conducted to the straight horizontal portions 7' and 8, which are adapted to form that portion upon which the feet are supported. It will also be seen that the attaching bolts 12 passing through the loop 4 can be moved so that the device can be attached to radiators in which the heating coils are arranged a greater or less distance apart or where the coils are of greater or less diameter.

Having thus fully described my invention what I claim is:

1. A radiator foot rest comprising two vertically spaced rods and having their ends bent around and extending parallel with the body portion and spaced therefrom and formed into vertically disposed loops through which clamping bolts pass.

2. A radiator foot rest comprising two rods looped midway their ends and bent around forming two loops parallel with the rod and spaced therefrom and the ends of the rod abutting and electrically welded and a plate welded to the rod and covering the joint between the ends thereof and attaching bolts passing through the looped ends of the rods and clamping the same to the coils of the radiator.

In testimony whereof, I have signed this specification.

PERCY C. AVERY.
